UNITED STATES PATENT OFFICE.

ADOLF O. GRAF, OF DEMAREST, NEW JERSEY, ASSIGNOR TO THE MANHATTAN OPTICAL COMPANY, OF NEW YORK.

GRIPPING DEVICE FOR CAMERA-FRONTS.

SPECIFICATION forming part of Letters Patent No. 654,790, dated July 31, 1900.

Application filed May 1, 1900. Serial No. 15,027. (No model.)

To all whom it may concern:

Be it known that I, ADOLF OTTO GRAF, a citizen of the United States, and a resident of Demarest, in the county of Bergen and State 5 of New Jersey, have invented certain new and useful Improvements in Gripping Devices for Camera-Fronts, of which the following is a specification.

The object of my invention is to provide a 10 new and improved gripping device for camera-fronts which shall be of simpler construction and more conveniently operated than those hitherto employed.

In the accompanying drawings, Figure 1 is 15 an isometric perspective of my improved gripping device applied to a camera-front. Fig. 2 is a vertical cross-sectional view of the same. Fig. 3 is a view of the flexible bottom plate looking at it from the under side.

20 Similar reference-letters denote similar parts throughout the several views.

A is the extensible front of a collapsible camera of the usual construction, which is arranged to be moved forward or backward 25 on the hinged support B when the camera is being opened or closed and also to obtain an approximate focus. It is guided in its movements by the track C, carried on the support B. The track C is made of a long narrow 30 strip of brass, with the longer edges thereof bent up and at right angles to form flanges, as shown in Fig. 1. A portion of this track is shown in Fig. 1 as broken away directly in front of the gripping device attached to 35 the camera-front in order that the engagement of the bottom plate of the gripping device with the track C may be more clearly perceived. To the under side of the extensible front is attached the bottom plate D, the bottom view of which is seen in Fig. 3. At the outer side edges this plate D is bent 40 over to form gripping-flanges E E, which engage with the flanges of the track C.

At the center of this plate D and near the 45 forward end thereof a perforation is made, through which there passes a screw-threaded bolt F, Fig. 2. In the plate D and behind the point through which the bolt F passes are cut two slots G G, Fig. 3. The effect of these 50 slots is to render the forward portion of the plate D flexible, so that it may be readily

buckled by a pull at the center. When so buckled, it is evident that the gripping-flanges E E are drawn toward one another and will grasp tightly the flanges of the track C. The 55 rear portion of the plate D is rigid and provided with screw-holes, through which small wood-screws are passed to secure the plate to the bottom of the extensible front.

The plate D receives a shouldered nut H, 60 through which the screw-threaded portion of the bolt F passes. This nut H is held from rotation in the plate D by an adjustable means. The lower portion of the nut H is expanded into a flange, as shown in Fig. 2, 65 so that it may have a considerable bearing upon the lower surface of the flexible portion of the plate D. A portion of the wood of the camera-front is cut away directly above this nut and the adjacent parts of the 70 flexible portion of the plate D in order that said flexible portion may have room to buckle in an upward direction when an upward pull is exerted on the nut H by the screw-bolt F. At the upper end of the screw-bolt 75 and fast thereto is a lever I, having two finger-pieces M and N. The finger-piece M is at the extreme outer end of the lever I and serves to oscillate it. This lever affords naturally a convenient hand-grasp to draw 80 out the extension-front when opening the camera; but if it is grasped at the point M the first effect of a pull is to cause the lever to swing forward into the axial line of the camera or that line along which the pull is 85 exerted, in which position the gripping device is in partial engagement with the track C and offers considerable resistance to movement along the same. I therefore provide the integral finger-piece N adjacent the pivot 90 and so placed on the lever I that it is presented to the front to be conveniently seized when the lever I is at the extreme right-hand position, in which position of the lever the gripping device is disengaged from the track 95 C, as explained later. As the finger-piece N is at this time in the line in which force is to be exerted, the lever I has no tendency to swing on the application of the pull at the point N. On the contrary such pull positively 100 operates to keep the lever in its right-hand or loose position during the adjustment

of the extension-front. In cameras having a separate hand-hold independent of the gripping-lever for moving the extension-front the liability of the lever to swing accidentally and clamp the gripping device during an adjustment of the extension-front frequently causes annoyance. This inconvenience is avoided by my arrangement. The finger-piece N is serviceable in moving the extension-front either forward or backward.

The direction of twist of the screw-threads on the screw-bolt F is such that when the lever I is in the right-hand position the gripping-plate D is in its lowered position, and the flanges E E are not gripping the flanges of the track C. When the lever I is swung around to the left-hand position, the nut H is drawn upward by the bolt F, drawing with it the adjacent portion of the plate D. This drawing up or buckling of the plate D causes the flanges E E to approach one another and to grip tightly the flanges of the track C, so that no movement of the camera-front along the track can occur until the loosening of the gripping device by the return of the lever I to its original right-hand position.

The screw-bolt F is prevented from moving downwardly through the nut H by a small plate K on the upper side of the forward projection P of the camera-front. The screw-bolt passes through this plate and bears on it by a small shoulder, formed just beneath the lever I, as clearly seen in the cross-sectional view Fig. 2. Two small vertical pins or stops L L are placed back of the lever I to limit its movement in either direction.

The means by which the nut H is adjustably secured to the plate D are as follows: In the plate D are three holes Q. (See Fig. 40 3 in dotted lines.) A pin R, passing through the flange of the nut H, enters one of these holes. If it is desired to tighten the grip on the track, the pin is removed and the nut H rotated for a third of a revolution, so that 45 the pin can enter the next hole, the result being to raise the nut permanently a short distance on the screw-bolt F. This occasions a greater buckling of the plate D and consequently a tighter grip of the flanges E on the 50 track C when the lever I is operated in the usual manner.

Having described my invention, what I claim, and desire to secure by Letters Patent, is—

55 1. In a gripping device for camera-fronts, the combination of a flanged track, a flexible plate with a single perforation, gripping-flanges on the plate, to engage with the flanged track, and means engaging the plate 60 at the perforation for buckling the plate, whereby its flanges are brought into engagement with the flanged track, substantially as described.

2. In a gripping device for camera-fronts, the combination of a flanged track upon 65 which the camera-front is adapted to run, a flexible plate beneath the camera-front and extending over the flanged track, flanges on the said flexible plate adapted to engage with the flanged track, a screw-threaded nut beneath the flexible plate, a screw-bolt passing through the flexible plate and entering the nut, and means for turning the screw-bolt, whereby the nut may be drawn upon the screw-bolt and the flexible plate buckled, to 70 bring its flanges into engagement with the flanged track, substantially as described.

3. In a gripping device for camera-fronts, the combination of a flanged track upon 75 which the camera-front is adapted to run, a flexible plate beneath the camera-front and extending over the flanged track, flanges on the said flexible plate adapted to engage with the flanged track, a screw-threaded nut beneath the flexible plate, a screw-bolt passing 80 through the flexible plate and entering the nut, means for preventing longitudinal movement of the screw-bolt, and means for turning the screw-bolt, whereby the nut may be drawn upon the screw-bolt and the flexible plate buckled, to bring its flanges into engagement with the flanged track, substantially as described.

4. In a gripping device for camera-fronts, the combination of an extension-front, a support 95 on which the extension-front may run, a flexible plate carried by the extension-front, and engaging the support, and means for bringing the flexible plate into close engagement with the support to prevent longitudinal movement of the extension-front thereon, substantially as described.

5. In a gripping device for camera-fronts, the combination of a support for the camera-front, gripping means engaging with the support, a lever to operate the gripping means, pivoted at one end and having a finger-piece at the other end, and an offsetting finger-piece integral with the lever and located adjacent to the pivot whereby it is presented to 105 the hand when the lever is in the unlocked position, substantially as described.

6. In a gripping device for camera-fronts, the combination of a support for the camera-front, gripping means for engaging with the support, a pivoted lever to operate the gripping means, and pins to limit the swing of the lever in either direction, substantially as described.

In testimony whereof I have signed my 115 name to this specification in the presence of two witnesses.

ADOLF O. GRAF.
